UNITED STATES PATENT OFFICE.

BYRON J. SIMPSON AND HENRY L. MANDERVILLE, OF WILLOW, CALIFORNIA.

DESIGN FOR AN ATTACHMENT FOR AUTOMOBILE RADIATOR-TOPS.

45,275.

Specification for Design.

Patented Feb. 17, 1914.

Application filed November 15, 1913. Serial No. 801,261. Term of patent 3½ years.

To all whom it may concern:

Be it known that we, BYRON J. SIMPSON and HENRY L. MANDERVILLE, citizens of the United States, residing at Willow, in the county of Glenn and State of California, have invented a new, original, and ornamental Design for an Attachment for an Automobile Radiator-Top, of which the following is a specification, reference being had to the accompanying drawing, forming part thereof.

The figure is a perspective view of an ornamental attachment for an automobile radiator top embodying our new design.

We claim:

The ornamental design for an attachment for an automobile radiator top, as shown.

BYRON J. SIMPSON.

HENRY L. MANDERVILLE.

Witnesses:

CLYDE C. CANFIELD,

GEORGE A. BARROW.
